UNITED STATES PATENT OFFICE.

PARVIN WRIGHT, OF CHICAGO, ILLINOIS.

ELECTRIC FURNACE AND METHOD OF OPERATING THE SAME.

Application filed February 16, 1922. Serial No. 536,995.

To all whom it may concern:

Be it known that I, PARVIN WRIGHT, a citizen of the United States, residing at Chicago, in the county of Cook and State of Illinois, have invented certain new and useful Improvements in Electric Furnaces and Methods of Operating the Same; and I do hereby declare the following to be a full, clear, and exact description of the invention, such as will enable others skilled in the art to which it appertains to make and use the same.

This invention relates to electric furnaces and has for its object to provide an apparatus for melting or smelting ores and other materials, which will be comparatively inexpensive to construct and more efficient in action than those heretofore proposed.

With these and other objects in view, the invention consists in the novel details of construction and combination of parts more fully hereinafter disclosed and particularly pointed out in the claims.

Referring to the accompanying drawings forming a part of this specification, in which like numerals designate like parts in all the views:

Figure 1 is a vertical sectional view of one form of furnace made in accordance with this invention;

Figure 2 is a sectional view of a somewhat modified form of furnace;

Figure 3 is a diagrammatic cross sectional view of a furnace similar to those shown in Figures 1 and 2 and illustrating the stack, feed chute and a slag spout;

Figure 4 is a sectional view of a still further modified form of the invention especially adapted for a three-phase current;

Figure 5 is a detail view illustrating a modified form of heating elements; and

Figure 6 is a diagrammatic view illustrating a still further modified arrangement of the heating elements.

In order that the invention may be the better understood it is said: This furnace is especially adapted for melting and smelting pocket ores that are found in California, Oregon, and the Pacific coast generally. In the regions where these ores are found, sources of electric current are available but such sources may sometimes be single phase, two phase, or three phase, and therefore, it is very desirable to adopt such a form of furnace as will lend itself readily to currents of one or more phases. That is to

say, as is well known, in changing from a current of one phase to a current of two or more phases, it is often necessary to change the number of electrodes, and in many cases it is desirable to change the winding of the transformers and certain of the electrical connections. But these changes can be readily accomplished by the skilled workmen and when furnaces of the character of those herein illustrated are adopted these said changes are readily carried out.

Referring to the drawings, 1 indicates any suitable furnace walls preferably of brick work which are surrounded by the metallic casing 2 to hold the parts together, should they crack or otherwise deteriorate. 3 indicates a stack for carrying away the noxious gases, 4 indicates a hearth for holding the molten material, 5 a spout or passage to draw off the molten metal or other material, and 6 a slag spout for drawing off the slag.

In the form of furnace illustrated in Figures 1 and 2, the electrodes 10 may be readily joined in a single phase circuit indicated at 11, while in the form shown in Figure 4, the electrodes 7 may be joined in the primary circuit 8 and 9, of the three phase system. The induction coils 12 and 13 are carried by the circuit connections 8 and 9 and the induction coils 14 and 15 are located in inductive relation to said coils 12 and 13 to feed the circuits connected therewith. That is to say, the coil 14 feeds current to an electrode 16, see Figure 4, which may be one of a pair of electrodes, and the coil 15 feeds current to the resistor heaters 18, 19 and 20, as shown.

In all the forms of the furnace, the electrodes are or may be adjustable up and down by a suitable and well known means not shown, and the ore or other material to be melted or smelted is conveniently fed into the stack 3 by means of the chute 21 through the opening 22 normally closed by the door 23. The furnace bodies are cut away as illustrated to form arched over roofs while in Figure 4 the said body is cut away to form the annular space 25 as shown. The roof of the furnace bodies is provided with openings as illustrated, which openings are closed by one or more cover plates 26, provided with holes 27 through which the electrodes are passed. The annular space 25 illustrated in Figure 4 widens out somewhat below the top of the furnace

and terminates in the crucible or hearth space at the bottom of the furnace.

The charge material, on the other hand, descends through the central space 29, which extends substantially down to the normal level of the molten material and thus is prevented from striking the electrodes and mechanically injuring the same.

The charge material being thus introduced onto the hearth of the furnace, it may be readily heated by the resister elements 18, 19, and 20 as follows: The current passing through the elements 18 and 20 of necessity has to pass through the element 19 which lies on top of the elements 18 and 20. The somewhat poor contact thus provided between the element 19 and the elements 18 and 20 causes the element 19 to be readily heated up to a high temperature. This action is enhanced by so regulating the size and dimension of the element 19 as to facilitate its being raised to a high temperature, and in addition to this, in many cases the element 19 will be made of carbon, while the elements 18 and 20 will be made of a good conducting material such as metal copper matte or magnetic iron oxide Fe_3O_4 . In all cases, the heat will be concentrated in the element 19 and conducted from said element 19 to the charge.

In order to still further facilitate the heating of the charge, I provide at each end of the element 19 a mass of finely divided carbonaceous or other semi-conducting material 30, as shown, so that current will readily pass from the elements 18 and 20 through said material 30 and from said material 30 through the charge, as it becomes more and more heated. Between the carbonaceous or other masses 30 I further provide the somewhat insulating material 31 which may be conveniently made of clay.

This entire heating element 19 is in a secondary circuit as shown, with the secondary voltage regulated to suit the conditions of the furnace. Accordingly, it results that when the current is first turned on, before the ore is heated to a high temperature a large percentage of the current passes through the carbon resister 19, heating it and the entire lower body of the furnace. As the ore gradually heats up part of the secondary current leaves the carbon resister 19 and flows through the carbonaceous or chromite materials 30 and through the ore, thus increasing the heating of the latter, so that the primary electrodes 7 will begin to pass current through the ore, and thus will pass current through the ore, and thus will 60 the entire charge of ore be rapidly melted.

It will be observed from Figure 2 that the elements 20 are two in number and of course it will be readily understood that the elements 18 may likewise be two in 65 number in order to carry a greater volume

of current and to keep down the temperature in the elements 18 and 20. It will also be observed that there is a considerable space reserved in the brickwork 1 to accommodate the elements 18, 19 and 20, 70 and that, as shown in Figure 2, this space is partially filled with a refractory material 32 which may be of clay or other well known refractory substance, so that the heating elements do not come in contact with the furnace walls. 75

In addition to this refractory material 32, there is an air space 33 surrounding the carbon element 19, and thus is the said element still further insulated from the heating 80 walls. The refractory material 32, however, serves to effectually seal the carbon element 19 from the outer air, and thus is the combustion of said element 19 prevented. When it is desired to renew the elements 18, 19, 85 or 20, or any one of the same, it is only necessary to remove a few brick near the sides of the furnace to remove the elements 18, 19, and 20, and to slip in a new assemblage 90 of elements 18, 19, and 20, which have been prepared on the outside of the furnace, whereupon the space may be readily bricked up at each side of the furnace and the new carbon element 19 sealed in out of contact 95 with the air. All of this is accomplished without disturbing the furnace linings. 100

In the somewhat modified form of invention illustrated in Figure 5, the heating elements are substantially the same as in Figure 4, except a conducting mass 35 of copper matte, iron oxide, or highly conductive chromite ore is provided, which joins the carbonaceous masses 30 and a by pass conducting member 36 having a coil 37 of a small number of turns. Said member 36 joins the elements 18 and 20 as shown, and is in inductive relation with the coil 38 having a relatively large number of turns of which is fed from the source of current 39. An electrode 40 is placed in contact 110 with the mass 35.

In this particular form of heating element, the current from the source 39 passing through the coil 38 will be converted from a high voltage into a low voltage of great quantity and such converted current will readily heat up the carbon element 19, the carbonaceous masses 30 and ore mass 35, and the electrode 40 passing down through the ore to be melted will be withdrawn from 115 said mass 35 as fast as the ore heats up, so that the entire charge will be melted in a very short space of time. 120

In the still further modified form of heating elements shown in Figure 6, the conducting members 18 have led across their top surfaces the heating element 19 which is reduced in cross section as at 42, so that it heats more readily than would be the case 125 if it were of a uniform section. 130

It will now be seen that in all the forms of the invention the furnace may be simply and quickly constructed of ordinary brick-work, the heating elements are readily brought 5 to a high temperature, and impart a high degree of heat to a portion of the charge, thus rendering that portion conductive, so that additional current may pass therethrough from primary or secondary electrodes.

It will further be noticed that either a single or multiple phase current may be employed, and that the electrodes proper may be used as arc electrodes or they may be 15 immersed in the charge and used as resistors according to the nature of the material to be treated.

It will further be observed that in the form shown in Figure 4, the chute 21 and 20 opening 22 into the space 29 are so located that the material is delivered to the hearth in such a way that it cannot injure the electrodes in its fall, and that a large, open, unobstructed hearth is provided. It will still 25 further be observed that owing to the above mentioned features one is enabled to make a furnace of unusual strength with a minimum of materials and in a minimum of time.

It is obvious that those skilled in the art 30 may vary the details of construction as well as the arrangement of parts without departing from the spirit of the invention, and therefore I do not wish to be limited to the above disclosure except as may be required 35 by the claims.

What I claim is:

1. An electric furnace provided with a primary circuit including an arc electrode; a secondary circuit in inductive relation to 40 said primary circuit and including a resistor; comprising a pair of metal conductors with a superposed carbon conductor;

means for preventing the charge material from contacting with said conductors; and means for connecting electrically a charge 45 of ore in the furnace in multiple with said resistor.

2. An electric furnace provided with a manhole top through which a primary electrode passes; a chute to one side of the 50 chamber with an archway between; means for the gases to escape and for the ore to enter through said chute in combination with a secondary conductor below the hearth comprising a pair of metal conductors surmount- 55 ed by a carbon conductor and masses of semi-conducting material, the whole constituting a heating element with a parallel circuit through the ore.

3. An electric furnace provided with a 60 charge of material therein; means to supply heat to the top of the charge from one circuit; means comprising a pair of metallic bars surmounted by a carbon rod and masses of semi-conducting material separated by 65 insulating material to supply heat from below the charge by another circuit; and additional means for passing all of said circuits through the charge at different angles. 70

4. An electric furnace provided with a charge of material; means of passing the primary circuit through said material vertically; means comprising a pair of metallic bars surmounted by a carbon rod and masses of semi-conducting material separated by insulating material for passing the secondary circuit through said charge horizontally; and additional means for supplying heat from below the hearth by heating the bottom of the furnace, all from the same energizing circuit. 75

In testimony whereof I affix my signature.
PARVIN WRIGHT.
